UNITED STATES PATENT OFFICE

110,980

DESIGN FOR AN INCLINOMETER OR THE LIKE

William H. Reardon, Newark, N. J.

Application December 4, 1937, Serial No. 73,378

Term of patent 3½ years

To all whom it may concern:

Be it known that I, William H. Reardon, a citizen of the United States, residing at Newark, in the county of Essex and State of New Jersey, have invented a new, original, and ornamental Design for an Inclinometer or the like, of which the following is a specification, reference being had to the accompanying drawing, forming part thereof.

Figure 1 is a view in front elevation of an

inclinometer or the like, showing my new design.

Figure 2 is a top plan view thereof.

Figure 3 is a side elevational view.

The words and numerals appearing on the design in Figure 1 are merely illustrative.

I claim:

The ornamental design for an inclinometer or the like, as shown and described.

WILLIAM H. REARDON.
